United States Patent [19]
Nagata

[11] Patent Number: Des. 316,716
[45] Date of Patent: ** May 7, 1991

[54] AMPLIFIER

[75] Inventor: Shunsaku Nagata, Yokohama, Japan

[73] Assignee: Kabushiki Kaisha Toshiba, Kawasaki, Japan

[**] Term: 14 Years

[21] Appl. No.: 207,443

[22] Filed: Jun. 16, 1988

[30] Foreign Application Priority Data

Dec. 17, 1987 [JP] Japan 62-51283

[52] U.S. Cl. D14/188

[58] Field of Search D14/188, 265, 299, 169
